UNITED STATES PATENT OFFICE.

HERMAN WIPF, OF NARBERTH, PENNSYLVANIA, ASSIGNOR TO JOHN WYETH & BRO.,
INC., OF PHILADELPHIA, PENNSYLVANIA, A CORPORATION.

DESIGN FOR AN ANTISEPTIC TABLET.

55,542.

Specification for Design.

Patented June 22, 1920.

Application filed September 23, 1919. Serial No. 325,781. Term of patent 14 years.

To all whom it may concern:

Be it known that I, HERMAN WIPF, a citizen of the United States, residing at Narberth, in the county of Montgomery, State of Pennsylvania, have invented a new, original, and ornamental Design for Antiseptic Tablets, of which the following is a specification, reference being had to the accompanying drawing, forming part thereof.

The figure is a perspective view of an antiseptic tablet showing my new design.

I claim:—

The ornamental design for an antiseptic tablet, as shown.

HERMAN WIPF.
